(57) **CLAIM**

The ornamental design for a “cup,” as shown and described.

DESCRIPTION

FIG. 1 is a perspective view of a cup showing our new design;

FIG. 2 is a top plan view of the cup of FIG. 1;

FIG. 3 is a front elevational view of the cup of FIG. 1; the rear elevational view being a mirror image thereof;

FIG. 4 is a left side elevational view of the cup of FIG. 1, the right side elevational view being a mirror image thereof; FIG. 5 is a bottom plan view of the cup of FIG. 1; and, FIG. 6 is an environmental perspective view thereof.

The dashed lines are for illustrative purposes only and form no part of the claimed design.
